UNITED STATES PATENT OFFICE.

FREDERICK W. MARTIN, OF NEW YORK, N. Y., ASSIGNOR TO J. S. COFFIN, OF NEW YORK, N. Y.

SPRINKLER DEVICE FOR LOCOMOTIVES.

1,147,418.

Specification of Letters Patent. Patented July 20, 1915.

Application filed February 15, 1913. Serial No. 748,537.

To all whom it may concern:

Be it known that I, FREDERICK W. MARTIN, a citizen of the United States, residing at New York, in the county of New York and State of New York, have invented certain new and useful Improvements in Sprinkler Devices for Locomotives, of which the following is a specification.

This invention has reference to an improved form of sprinkler device for locomotives and is adapted, for example, for sprinkling the coal in the tender, cleaning, and for other analogous uses. It relates particularly to that class of locomotive sprinkler in which the discharge of the water and the operation of the sprinkler is accomplished by means of air pressure, and it has among its primary objects the provision of an improved means for storing a predetermined quantity of water for uses such as those specified, which storage means is simple, inexpensive and easy to assemble; and the provision of improved means for supplying the requisite air pressure for operating the sprinkler. My invention also contemplates the provision of an improved arrangement of piping connection when the air supply is drawn from the train pipe whereby to prevent excessive discharge of air in case of breakage, etc., as will hereinafter more fully appear. A further object of the invention resides in the provision of a valvular control device whereby the pipes may be thoroughly cleared of water after use, thus avoiding freezing in the pipes in cold weather. These, together with such other objects as may hereinafter appear or are incident to my invention, I attain by means of a construction, various embodiments of which are illustrated in preferred form in the accompanying drawings, wherein:

Fig. 1 is a partial longitudinal section through a portion of a locomotive tender illustrating the application of one form of my invention thereto; Fig. 2 is a transverse section through the tender; Figs. 3, 4 and 5 are sectional views of details of the invention; Fig. 6 is a sectional view similar to Fig. 1 but illustrates another embodiment of the invention; and Fig. 7 illustrates another application of my invention.

Referring now particularly to Figs. 1 and 2, it will be seen that I have illustrated a portion of one of the water legs or compart-

ments 7 of a locomotive tender, and also a part of the firing deck 8 to more clearly point out the operative relation and position of the parts. Lying within the leg 7 is a water reservoir 9 which comprises a casing 60 or pipe section 10 threaded at each end for engagement with an intake cap 11 and a discharge cap 12. The caps are provided with brackets 13 which serve as a means for attaching the reservoir to the wall of 65 the tender.

The intake cap 11 is enlarged to receive the casing 14 of a piston check valve 15 which permits water from the tender to flow freely into the reservoir but prevents it 70 from being blown back into the tender when the water in the reservoir is being expelled by the air pressure.

Bolted to the top of the leg 7 is an air reservoir 16 which is of substantially the 75 same construction as the water reservoir. Air under pressure is supplied to the reservoir from the train pipe 17 by means of the pipe 18 and hollow plug 19 which is tapped into the cap of the reservoir. Air from the reservoir 16 is supplied to the water reservoir by means of a pipe 20 which opens into the casing 14, in a manner hereinafter described, and which is controlled by the three-way 80 cock 21.

The water is carried from the water reservoir by means of the discharge pipe 22 to the end of which is connected a section of hose 23 or other flexible pipe. The pipe 22 is connected to the three-way cock 21 by 85 means of a branch pipe 22^a, and the pipe 18 is connected to the train pipe by the T 24, and threaded bushing 25, which is provided with a restricted orifice 26 which is clearly 90 illustrated in Fig. 3.

Attention is now directed to the intake of the water reservoir illustrated in section on a larger scale in Fig. 4. From an inspection of this figure, it will be seen that the casing 14 comprises a valve cylinder closed at the 10 bottom by a cap 27 and provided at the top with a shoulder 28 threaded into the cap 11. The cylinder is open at the top and water from the tender has free access to the valve chamber. Mounted within the cylinder is a valve piston 29 carrying a valve disk 30 adapted to seat on the valve seat 31. A port 32 is formed in the casing and opens into the valve chamber beneath the piston 29, this port being connected to the pipe 20.

A second port 33 is formed in the casing and establishes communication between the valve chamber and the water reservoir. Beneath the valve seat 31 the casing is provided with a plurality of ports 34 opening to the interior of the water reservoir. When the valve is open, water from the tender flows into the valve chamber and thence into the water reservoir through the ports 34, the port 33 being closed when the valve is in this position. The water in entering the valve chamber passes through the screen 35 which excludes dirt or other matter which might cause the valve to stick.

15 The three-way cock 21 is illustrated in section in Fig. 5, from inspection of which it will be seen that the port 21^a of the cock, when in one position, establishes communication between the reservoir 16 and the pipe 20, and when in the other position, between the reservoir 9 and the sprinkler hose through the pipe 22^a and the pipe 20.

The operation of the mechanism thus far described is as follows: The three-way cock 21 is turned to admit air under pressure to the pipe 20, from which the air enters the port 32 beneath the valve piston 29 which is elevated and seats the valve disk 30, thereby cutting off communication between the tender and the water reservoir. This movement of the valve piston uncovers the port 33 and the air passes out through said port into the water reservoir and expels the water through the pipe 22 into the sprinkler hose. In cold weather it is desirable to expel all the water from the sprinkler hose after it has been in use in order to avoid freezing, and to accomplish this, the three-way cock is turned to permit the air remaining in the water reservoir to flow back through the pipe 20 to the pipe 22^a, this being sufficient to expel the water left in the discharge or sprinkler pipe.

Air from the train pipe is supplied to the reservoir 16 through the port 26 in the bushing 25, but owing to the restricted character of the port 26, only a predetermined fixed flow from the train pipe is permitted so that any excessive discharge, caused for example by breakage in either of the pipes 18 and 20 will not cause a heavy discharge from the train pipe such as would effect the setting of the train brakes.

From the foregoing, it will be clear that a predetermined quantity of water is constantly at the disposal of the fireman and can be used without incurring danger of scalding or other injury through back flow of steam or hot water, as frequently occurs when the sprinkler hose is connected to the injector mechanism. The arrangement of parts is compact, simple and the device is efficient in operation. The reservoirs are of simple and inexpensive construction and can be readily assembled or taken apart, and the

entire apparatus can be supplied to any standard type of locomotive tender.

Referring now to the embodiment illustrated in Fig. 6, it will be seen that the air expelling the water from the reservoir 9 is supplied directly from the train pipe 17, by means of a pipe 18^a which leads to the intake end of the reservoir. The pipe 18^a is connected to the trainpipe by a T and bushing of the same construction as those previously described, so that discharge of pressure resulting from a breakage will not cause a similar discharge from the trainpipe. As in the construction previously described, a three-way cock 21 is provided for controlling the admission of air into the reservoir, and the water is expelled through the discharge pipe 22 to the sprinkler hose 23. The pipe 22 is connected to the three-way cock by the pipe 22^a, whereby the water remaining in the hose 23 may be expelled after use.

In Fig. 7 I have shown the same general arrangement illustrated in Fig. 6, but in this case I have connected the inlet pipe 18^a to the pipe leading to the valve 37 which controls the operation of the water scoop. In order to prevent any excess discharge from the piping connections for the water scoop valve, I have provided a bushing 25^a adjacent the three-way cock 21, which is of the same construction and is designed for the same purpose as the bushing 25.

It will be seen that after use there may be a siphonic action due to the presence of water in the upper part of the pipe 22 and the sprinkler pipe 23 whereby the water in the tender will be drawn out and continue to discharge through the sprinkler pipe. By turning the valve 21 so that the air remaining in the water reservoir flows back through the pipe 20 to the connection 22^a, the water in the sprinkler pipe is expelled and the water in the pipe 22 remaining above the normal level of the water will flow back, whereby the suction is broken and siphoning prevented.

Having thus described my invention and illustrated its use what I claim as new and desire to secure by Letters Patent is the following:

1. A sprinkler device for locomotives comprising in combination a main water tank, a reservoir, a valve normally establishing communication between the main tank and the reservoir, a discharge pipe leading from the reservoir, a pipe for supplying air pressure to the reservoir, said valve being moved to cut off communication between the main tank and the reservoir when air pressure is supplied to the latter, and a valvular device common to the discharge pipe and the air supply pipe adapted when moved in one position to admit air into the air supply pipe to expel the water from the reservoir

into the discharge pipe, and when in another position to admit air to the discharge pipe to expel the water remaining therein.

2. A sprinkler device for locomotives comprising in combination a main water tank, a reservoir, a valve, normally establishing communication between the main tank and the reservoir, a discharge pipe leading from the reservoir, a pipe for supplying air pressure to the reservoir, said valve being moved to cut off communication between the main tank and the reservoir when air pressure is supplied to the latter, a source of air supply and a valvular device controlling the supply of air both to the air supply pipe and the discharge pipe adapted when moved in one

position to establish communication between the source of supply and the air supply pipe whereby to expel water from the reservoir into the discharge pipe, and when in another position to establish communication between the source of supply and the discharge pipe to expel the water remaining therein.

In testimony whereof I have hereunto signed my name in the presence of the two subscribed witnesses.

FREDERICK W. MARTIN.
